BARREL STACKING DEVICE

James Critz Weaver, Richmond, Va.

Application April 27, 1951, Serial No. 223,358

5 Claims. (Cl. 214—10.5)

1

This invention relates to the stacking of barrels and the like, more particularly to a device for use in stacking tobacco hogsheads so as to facilitate the transportation thereof.

More specific objects of the invention are to provide means including readily removable chocks or braces for maintaining a plurality of hogsheads in stacked, superposed relation on a truck so that a relatively large load can be arranged in a relatively small space; so that relative shifting of the hogsheads with respect to each other and to the truck will be prevented; so that the hogsheads can be unloaded with facility when desired; and so that the problem of returning the equipment for reuse at the same starting point will be reduced to a minimum.

A preferred embodiment of the invention is illustrated in the accompanying drawing in which:

Fig. 1 is an end elevation of two superposed tiers of barrels arranged in a row extending transversely of a truck and showing a stacking device in accordance with this invention applied thereto.

Fig. 2 is an enlarged fragmentary perspective disassembled view of the stacking device.

Fig. 3 is an enlarged fragmentary side elevation of the stacking device.

Fig. 4 is a top plan of the structure shown in Fig. 3.

Fig. 5 is a vertical section taken on the line indicated at 5—5 of Fig. 4.

Fig. 6 is an enlarged end elevation of the stacking device.

Referring to the drawing in detail, the numeral 1 indicates the bed of a truck having suitably secured abutment rails 2 extending along the sides and throughout the length thereof. Mounted on the truck 1 are a plurality of barrels 3 arranged in a row extending transversely of the truck and consisting of upper and lower superposed tiers 4 and 5 respectively. A fully loaded truck would comprise additional similarly constituted and arranged rows so as to utilize fully the usable length of the truck.

Disposed between the tiers 4 and 5 is a stacking device in accordance with this invention and including a flat bar or board 6. Located at each end of the board 6 are a pair of plates 7 and 8 secured to the upper and lower faces respectively of the board. The plates 7 and 8 are of greater width than the board and side edge portions thereof project beyond the side edges of the board as indicated at 9.

Slidably mounted on each of the plates 7 is a

chock 10 which is removably secured to the plate by straps 11 countersunk in the lower face thereof and having U-bent end portions 12, each receiving a projecting edge portion 9 therein. Projecting from a recess 13 in the chock 10 is a pivotally mounted spring pressed pawl 14 for engagement with a row of apertures 15 through the plate 7. By way of example, the pawl is shown mounted intermediate its ends on a pin or bolt 20 extending transversely of and entirely through the chock, with a spring 21 bearing against the inner end of the pawl so as to bias the outer end thereof toward the apertured plate.

An identical chock 16, disposed upside down with respect to the chock 10, is slidably secured to the plate 8, which also is provided with a row of apertures 15. Permanently secured to the lower face of the board 6, midway the length thereof, is a substantially triangular spreader 17 for engagement with the barrels 3 of the lower tier 5.

Supported on the bed 1, between each rail 2 and the adjacent barrel 3, is a plate 18 similar in every respect to the plates 7 and 8 except the plates 18 are slightly shorter. Each plate 18 abuts a rail 2, and seated on each plate 18 is a chock 19 similar to and functioning in the same manner as the chocks 10, being held against the barrels in the tier 5 by the engagement of pawls 23 with the apertured plates 18. Preferably the chocks 19 are slidably secured to the plates 18 by means of straps 22 similar in every respect to the straps 11, and the plates 18 are secured to relatively short and thin boards 24. Preferably the plates 18, 7 and 8 are provided at their inner ends with stops 25 for cooperation with the associated pawls and apertures to maintain the chocks and plates in assembled relation when not in use.

Conveniently, the boards 6 and 24, spreader 17 and chocks 10, 16 and 19 may be formed of solid wood, with the plates, pawls and securing straps formed of metal, although the material employed is unimportant so long as it possesses the required strength without unnecessary weight.

In use, a tier of barrels such as 5 is loaded on a truck, and a board 6 carrying lower chocks 16 at its ends is placed on the tier with the spreader 17 between the individual barrels thereof. The boards 24, plates 18 and chocks 19 are then placed, and the chocks 19 and 16 adjusted transversely of the truck so as to snugly hold the barrels against the spreader 17 which slightly spaces the barrels apart.

The upper tier 4 is then placed on the board,

and the chocks 10 slid into place and adjusted to hold the individual barrels of the tier in engagement with each other midway between the planes of the rails 2. Owing to the slight spacing of the barrels in the lower tier, the mutually engaging barrels of the upper tier will be disposed with their centers of gravity slightly inward of the centers of gravity of the barrels in the lower tier to reduce any tendency of side sway of the upper tier or of the two tiers as a unit, thereby tending to stabilize the load. Additional rows of upper and lower tiers may be loaded in the same manner.

When it is desired to unload the barrels, the chocks 10 are removed after disengaging their pawls 14 from the plates 7. In the event of any binding of the pawls, this may be relieved by applying a leverage tool, such as a crowbar, to one of the barrels, and if necessary, a suitable tool may be inserted under the pawl to aid in disengaging it from the plate. As soon as the chocks 10 have been removed, the upper tier barrels may be rolled or lifted off, and the board 6 with chocks 16 removed, after which the chocks 19 may be removed in the same manner as the chocks 10, permitting removal of the barrels in the lower tier.

Due to their relatively small size and compact nature, the idle stacking elements can be stored beneath the bed or in other unused space for return to the loading point or until again needed.

I claim:

1. A stacking apparatus for maintaining superposed upper and lower tiers of barrels in a transverse row on a truck provided with abutment rails comprising, apertured plates seated on the truck bed in contact with the rails, chocks slidably mounted on the plates and having pawls for engagement therewith to hold the chocks against the lower tier barrels, a board extending transversely of the truck between the upper and lower tiers of barrels, a centrally located spreader depending from the board between adjacent barrels of the lower tier to hold them slightly apart, apertured plates on the upper and lower faces of the board at both ends thereof and having marginal portions projecting beyond the side edges of the board, upper and lower chocks having straps with end portions slidably securing them to said marginal portions, and pawls on said upper and lower chocks for engagement with the apertured plates on the board to hold the upper tier barrels against each other and the lower tier barrels against the spreader.

2. A stacking apparatus for maintaining superposed upper and lower tiers of barrels in a transverse row on a truck provided with abutment rails comprising, plates seated on the truck bed in contact with the rails, chocks slidably mounted on the plates, said chocks and plates having coacting means to hold the chocks against the lower tier barrels, a board extending transversely of the truck between the upper and lower tiers of barrels and having a centrally located spreader de-

pending therefrom, plates on the upper and lower faces of the board at both ends thereof and having marginal portions projecting beyond the side edges of the board, and upper and lower chocks having straps with end portions slidably securing them to said marginal portions, said upper and lower chocks and plates connected therewith having coacting means to hold the upper tier barrels against each other and the lower tier barrels against the spreader.

3. A stacking device for maintaining upper and lower tiers of barrels in superposed relation comprising, a board extending transversely of the barrels between the upper and lower tiers thereof, a centrally located spreader depending from the board between adjacent barrels of the lower tier, apertured plates on the upper and lower faces of the board at both ends thereof and having marginal portions projecting beyond the side edges of the board, upper and lower chocks having straps with end portions slidably securing them to said marginal portions, and pawls on the chocks for engagement with the apertured plates to hold the barrels of the upper tier against each other and the barrels of the lower tier against the spreader.

4. A stacking device for maintaining upper and lower tiers of barrels in superposed relation comprising, a board extending transversely of the barrels between the upper and lower tiers thereof and having a centrally located spreader depending therefrom, plates on the upper and lower faces of the board at both ends thereof and having marginal portions projecting beyond the side edges of the board, and upper and lower chocks having straps with end portions slidably securing them to said marginal portions, said chocks and plates having coacting means for holding the barrels of the upper tier against each other and barrels of the lower tier against the spreader.

5. A stacking device for maintaining upper and lower tiers of barrels in superposed relation comprising, a board extending transversely of the barrels between the upper and lower tiers thereof, plates on the upper and lower faces of the board at both ends thereof and having marginal portions projecting beyond the side edges of the board, and upper and lower chocks having straps with end portions slidably securing them to said marginal portions, said chocks and plates having coacting means to hold the chocks against the upper and lower tiers of barrels to prevent lateral displacement thereof.
